(57) **CLAIM**

The ornamental design for a four cell integrated transducer, as shown and described.

DESCRIPTION

FIG. 1 is a rear perspective view of a four cell integrated transducer showing our new design.

FIG. 2 is a rear perspective view thereof with the perforated material form.

FIG. 3 is a front perspective view thereof; and,

FIG. 4 is a front perspective view thereof with the perforated material form.

The broken line showing of the perforated material form is for illustrational purposes only and forms no part of the claimed design.
